UNITED STATES PATENT OFFICE.

HELAN HAILLS, OF CLINTON, MISSISSIPPI.

DESIGN FOR A CLOTHES HANGER.

Application filed May 6, 1922. Serial No. 2,106. Term of patent 3½ years.

To all whom it may concern:

Be it known that I, HELAN HAILLS, a citizen of the Republic of Germany, a resident of Clinton, county of Hinds, and State of Mississippi (whose post-office address is Clinton, Mississippi); have invented a new, original, and ornamental Design for Clothes Hangers, of which the following is a specification, reference being had to the accompanying drawing, forming part thereof.

The figure is a modification of a hanger showing my new design.

I claim:

The ornamental design for a clothes hanger, as shown.

In testimony whereof I affix my signature in the presence of two witnesses.

HELAN HAILLS.

Witnesses:

HENRY PRICE BALL,
FLORENCE A. CHAPPLE.
